GARMENT TENSIONING MEANS

Marcus Manly Isaacs, St. Leonards, New South Wales, Australia

Application August 20, 1948, Serial No. 45,336
In Australia September 24, 1947

8 Claims. (Cl. 2—237)

1

For the tensioning of waistbands of garments, for instance self-supporting trousers, it has been proposed in my Patent No. 2,474,629, dated June 28, 1949, to provide two pouches in spaced and opposite relationship on the waistband and to place in these pouches supporting members carrying respectively a hook and a co-operating engagement element, each supporting member having a base for accommodation in one of said pouches, the width and contour of which corresponds to the width and contour of the respective pouch. The arrangement of the pouches on the waistband is such that in use the bases of the supporting members transfer the closing strain evenly over the entire width of the pouches and hence of the waistband, and thus assist in keeping the waistband uncrumpled and provide greater comfort for the wearer.

A feature, common to the forms of tensioning means described in the specification of my said co-pending application, is that the base of one supporting member is associated with a hook element and the base of the other element with a co-operating eye element. In one specific variant described and shown in the prior specification, a resilient element is arranged between the two members, said resilient element being associated either with the hook member or with the eye member of the device.

It has been found that greater simplicity and economy in the production of tensioning means according to the last-mentioned variant, and of similar structures, can be achieved if the supporting members for insertion in the pouches of the waistband on the one hand, and the resilient element on the other hand, are separate integers suitable for releasable attachment to one another. These advantages are even more pronounced if the supporting members are of identical construction so as to be interchangeable.

With this in view the present invention relates to a modified and improved tensioning device for use on garments, comprising two pouches secured to the garment in spaced and opposed relationship, each said pouch having an open mouth and a closed bottom, two supporting members each having a base accommodated in one of the pouches each base having a transverse width and an end contour corresponding to the width and bottom contour respectively of its pouch, and a separate detachable connecting link for said supporting members, the arrangement and spacing of the pouches on the garment being such that, in use, the bases of the supporting members connected by said link are

2

urged into engagement each with the bottom of its pouch.

In the drawings, Figs. 1 to 6 show, each in perspective view and by way of example, various forms of supporting members according to this invention, whilst Figs. 1A to 6A depict, each in perspective view, a connecting link suitable for use with the supporting members illustrated respectively in Figs. 1 to 6.

10 Fig. 1 shows two spaced flaps A and A¹ in opposed relationship to one another on the waistband of a garment, for instance on a pair of trousers. The flaps A, A¹ are formed with pouches B, B¹, respectively, of suitable depth and of a width w which substantially equals that of the flap in which it is formed.

15 In the form shown in Fig. 1 the supporting members C, C¹ of the device each comprise a plate element or base 10 of sheet metal or other sheet material, the transverse width of which equals that of the pouch B or B¹ wherein it is accommodated for use. The contour at one end 11 of each element 10 corresponds accurately to that of the bottom of pouch B or B¹ respectively.

20 Near its opposite end each element 10 is provided with a pin 12, and between said pin and the end 11, a tongue 13 of spring wire is permanently secured to the element 10. The element 10 is slightly curved longitudinally and transversally as shown in Fig. 1 so as to constitute a shallow concavity which accommodates the pin 12 and tongue 13, and to correspond approximately to the contour of the closed garment in use.

25 30 Near its opposite end each element 10 is provided with a pin 12, and between said pin and the end 11, a tongue 13 of spring wire is permanently secured to the element 10. The element 10 is slightly curved longitudinally and transversally as shown in Fig. 1 so as to constitute a shallow concavity which accommodates the pin 12 and tongue 13, and to correspond approximately to the contour of the closed garment in use.

35 40 In use on the waistband or a section thereof, the members C, C¹ are inserted into the pouches B and B¹ respectively, and are joined by a strap D (Figs. 1 and 1A) of leather, rubber, or other suitable material which is formed with a number of holes 14, two of which are engaged over the pins 12 respectively of the supporting members C and C¹.

45 The tongue 13 of each member is sprung against its base plate 10 and in this way each member acts as a clip preventing unintentional disengagement of the member from its pouch after insertion therein. The tongues 13 in use also serve as guides for the strap D.

The closing strain is transmitted to the 50 pouches B and B¹, by the supporting members C and C¹ the plate elements 10 of which bear with their ends 11 against the bottom portions of these pouches, engaging these bottom portions over their entire widths w. Thus the members C, C¹ and band D tension the flaps A and

A^1 of the waistband across their entire widths, thereby minimising the formation of wrinkles, folds and other distortions of the waistband during wear of the garment, and also spreading the closing stress on the wearer over a greater area, to his greater comfort.

It will be seen from Fig. 1 that the supporting members C and C^1 are of identical construction and are, like the pouches B , B^1 , symmetrical each with respect to its longitudinal axis X , so that they can be mutually interchanged. This greatly facilitates the packing, as well as the use of the device.

Fig. 2 of the drawing depicts a modified form of supporting members C , C^1 which differ from those shown in Fig. 1 by the provision on the base 10 of a number of spaced pins 12^1 , 12^2 , 12^3 , permitting attachment of a connecting element D^1 in any one of various positions, for proper adjustment of the tensioning device.

The connecting element D^1 (Fig. 2A) is in this case provided with single loops 15 , 15 at its opposite ends, to be passed over selected pins of the two members C and C^1 , thus permitting regulation of the tension to be applied to the waistband.

In the variant of the supporting members C , C^1 depicted in Fig. 3, the base 10 of each element is formed with a returned tongue 16 the tip of which is returned to constitute a hook 17 . The tongue 16 of each member C , C^1 is sprung against its base plate 10 and thus acts as the clip which prevents undesired disengagement of the member from its pouch.

The members C and C^1 are each made of a blank of sheet material of suitable shape, folded to form the base 10 , tongue 16 and hook 17 . Each member is slightly curved to correspond to the contour of the garment in wear.

For tensioning the waistband the supporting members C , C^1 are joined by a detachable connecting link D^2 (Fig. 3A) which, in this case, consists of a rubber band 18 with eyes 19 secured to its ends, said eyes in use engaging the hooks 17 of the said tongues 16 , 16 .

Fig. 4 of the drawing shows a form of the tensioning means which differs from that according to Fig. 3 in that the tongues 16 are each provided with an eye 20 , which may be pressed out of the sheet material of which the members C and C^1 are made. Accordingly the connecting element D^3 (Fig. 4A) is provided at its opposite ends with hooks 21 which in use engage the eyes 20 of the tongues 16 , 16 .

In Fig. 4A the connecting element D is shown as comprising a flat metal coil spring 22 as its resilient element. It is to be understood, however, that the resilient element may alternatively be constituted by a rubber or other elastic band.

It is by no means indispensable for the two supporting members of the improved device to be identical. Fig. 5 shows a modification of the tensioning means according to this invention wherein member C is formed with a hook 23 returned from a tongue 16^1 , whilst member C^1 is provided at the end of tongue 16^2 with an eye 24 .

The connecting link D (Fig. 5A), the body of which consists of an elastic band 18 , is provided, accordingly, with an eye 25 at one end and with a hook 26 at the opposite end, the eye 25 in use engaging the hook 23 of member C , and hook 26 engaging the eye 24 of member C^1 .

It will be further seen from Fig. 5 that the two tensioning members C and C^1 may consist entirely of suitably profiled resilient framing made, for instance, of pressed steel, the tongues 16^1 and

16^2 being constituted by (wire) loops returned from one end of each base 10^1 respectively. The required resiliency of each base 10^1 is secured by the provision of gaps 30 in the end sections 31 of the base.

When inserted in the afore-mentioned pouches, the sides of the bases 10^1 of these members are slightly elastically compressed and thereby keep the flaps or other waistband parts containing the pouches in transversely taut condition.

The band 18 , in the variants described with reference to Figs. 3 and 3A, or Figs. 5 and 5A, need not necessarily be a resilient band as the device will also be operative if the body of the connecting element D is made of non-resilient material, for instance, canvas or webbing.

A further variant of the improved tensioning means shown in Figs. 6 and 6A differs from that illustrated in Figs. 3 and 3A in that the hooks on the tongues 16 of the members C , C^1 and the eyes 19 on the connecting element D are replaced, respectively, by the male elements 27 and female elements 28 of press studs.

It will be understood that within the scope and ambit of the present invention, the elements of the improved tensioning means are capable of still further modification and I do not intend, therefore, protection by Letters Patent to be limited to the details of construction and design as hereinbefore described and as shown on the accompanying drawing.

Thus, for instance, the tongue of each supporting member may be sprung against its base plate so as to act as a clip in the manner described. This permits easy detachment of the supporting member from the garment, and re-attachment, whenever required, for instance, for laundering, dry-cleaning, or pressing. Where, however, the member is sewn into a pouch of the flap or other part of a waistband, resiliency of the tongue in relation to the base would not be required.

The invention is not limited to hook-and-eye fasteners, or press studs, but may embody any other type of attachment.

45 I claim:

1. A tensioning device for use on a garment comprising two pouches secured to the garment in spaced and opposed relationship and each pouch having an open mouth and a closed bottom, the mouths of the two pouches being away from and the bottoms of the two pouches being towards one another, two supporting members each having a base accommodated in one of said pouches and slidably removable therefrom, each said base having a transverse width and an end contour corresponding to the width and bottom contour respectively of its pouch and a portion of each supporting member projecting from the pouch receiving the base of that member and towards the other pouch, and a separate connecting link detachably securable to the projecting portions of both said supporting members.

2. A tensioning device for use on a garment comprising two pouches secured to the garment in spaced and opposed relationship and each pouch having an open mouth and a closed bottom, the mouths of the two pouches being away from and the bottoms of the two pouches being towards one another, two supporting members each having a base accommodated in one of said pouches and slidably removable therefrom, each said base having a transverse width and an end contour corresponding to the width and bottom contour respectively of its pouch and being provided with a tongue exterior to the said pouch

sprung against said pouch, together with a separate detachable connecting link for said supporting members detachably securable to both said tongues.

3. A tensioning device as claimed in claim 1, wherein said supporting members and pouches are of identical construction and are each symmetrical about its longitudinal axis so that the supporting members are mutually interchangeable.

4. A tensioning device as claimed in claim 2, wherein each supporting member comprises a resilient frame structure contoured to constitute said base, and a loop returned from one end of said frame structure to constitute said tongue.

5. A tensioning device for use upon a garment as claimed in claim 1, in which at least one of the ends of the connecting link specified is arranged for connection to the supporting member associated therewith at any one of a plurality of points, the effective length of the connecting link being thereby variable.

6. A tensioning device for use upon a garment as claimed in claim 2 in which at least one of the ends of the connecting link specified is arranged for connection to the supporting member associated therewith at any one of a plurality of points, the effective length of the connecting link being thereby variable.

7. A tensioning device for use upon a garment as claimed in claim 1, in which the connecting link specified is of resiliently extensible material.

8. A tensioning device for use upon a garment as claimed in claim 2 in which the connecting link specified is of resiliently extensible material.

MARCUS MANLY ISAACS.
